GRINDING MACHINE

James A. Harrold, Clifton, N. J., assignor of one-half to Herman Pollack, Paterson, N. J.

Application August 23, 1939, Serial No. 291,589

2 Claims. (Cl. 51—101)

This invention relates to an improvement in lens edge grinding machines.

An object of this invention is to intermittently rotate the lens being ground and such rotary movement being imparted to the lens upon the removal of the glass down to size governed by a pattern. This construction differing from the present or generally accepted method for grinding lens wherein the lens and grinding wheel are both continuously rotating during the operation of grinding the lens down to size or shape.

In the present invention, the lens is held in contact with a continuously rotating grinding wheel until a desired amount of glass or material is removed whereupon the lens is rotated sufficiently to present another surface to the wheel, and so on until the lens has been given a complete rotation in producing the desired shaped lens. A pattern is provided for governing the amount of material to be removed. As each quantity of material is removed from the stationary lens, the pattern will be moved into a position for establishing a circuit whereupon suitable mechanism will be actuated for causing gear trains to be operated for rotating the lens a sufficient amount to bring a new surface in contact with the grinding wheel whereupon the circuit will be broken and the gear train stopped and a further grinding operation on the lens performed by the grinding wheel.

The invention consists further in novel driving means for imparting intermittent motion to the carriage supporting the lens and pattern so that upon the removal of a portion of the glass or material, composing the lens or other article, is removed from the stationary lens held and supported by the carriage, the driving mechanism will be operated for imparting a slight rotary movement to the lens to bring a new surface into contact with the grinding wheel, and upon the bringing of this new surface into contact with the grinding wheel, the driving mechanism will be discontinued and the material of the lens removed, and upon the completion of this grinding operation the driving mechanism will be again established and another cycle completed. In this manner a complete rotation of the lens will produce a finished product.

With this invention wherein the lens is ground down to finished size and shape upon a complete rotation of the lens, it has been possible to overcome the objection to the machines generally employed wherein the lens and grinding wheel are being rotated continuously. With this latter practice, irregular shapes and corners are produced

and it is necessary to disengage the carriage and stop the rotation of the lens and for the operator to determine by hand, that is by "feel," whether or not the lens has been ground to the proper shape and size and then causing the lens to be again brought into engagement with the grinding wheel for removing these rough or high spots that exist on the lens before it can be termed a finished product. Whereas, with this invention, these objections are eliminated and upon one complete revolution or in some instances one additional turn at a regular speed would assure a smooth edge and the lens would be completed at one-third the usual time now required without the necessity of being observed by an attendant to insure that all unfinished portions or high spots have been removed from the lens.

The invention consists of certain novel features of construction and combinations of parts which will be hereinafter described and pointed out in the claims.

In the accompanying drawings,

Figure 1 is a detailed view partly in section of the automatic means or control for governing the rotation of the lens to be ground.

Figures 2 and 3 are horizontal sectional views of the clutch mechanism shown in Figure 1. Figure 4 is a perspective view of a standard lens grinding machine having a portion broken away to better show the invention applied thereto.

Figure 5 is a view in side elevation of a portion of such standard machines showing some of the parts broken away to illustrate the driving mechanism for the lens supporting carriage.

Figure 6 is a detailed view in elevation showing the position assumed by the lens and pattern during the grinding operation of the present invention.

This invention is capable of being applied and used in conjunction with the standard machines and for the purposes of illustration the invention has been adapted to a rimless edge grinder. A portion of such machine as is believed sufficient for illustration has been disclosed in the drawings and will now be described for the purpose of obtaining an understanding of the present invention.

Referring to Figures 4 and 5, the numeral 35 represents the machine base or bed upon which is mounted for reciprocating movement a table 50. An arbor 36 is mounted in suitable bearings 37 on the base 35. Power is transmitted to the arbor 36 through a pulley 38 mounted thereon and a belt 39 transversing the pulley, which belt is connected to some suitable power supply, not 55

shown. Mounted on the arbor 36 is a grinding wheel or stone 48.

Table 51 is provided with two stanchions 52. Interposed between the stanchions and supported thereon for oscillation is a carriage consisting of housings 56 and 57 connected together by a tubular member 55, the housings 56 and 57 being connected by pivots or trunnions 53-54 to the stanchions 52. Journalled in the tubular member is a shaft 68 provided with gears 71, 72 at each end which are located within the housing 56, 57 respectively. A head spindle 77 is journalled in the housing 56 and is provided with a gear 76 which meshes with an idler gear 78 journalled in the housing and which idler gear meshes with the gear 71 of the shaft 68 whereby motion is imparted from the shaft 68 to the spindle 77. A tail spindle 78 is journalled in the housing 57 and is provided with a gear 76 which meshes with an idler gear 74 journalled in the housing 57 and which idler gear meshes with the gear 72 of the shaft 68 for imparting rotation from the shaft 68 to the tail spindle 78. The head spindle 77 and the tail spindle 78 are provided respectively with pad holders 80, 81 for supporting the lens material 82 to be ground. The head spindle 77 also carries a pattern 79 which will be of a size and shape that conforms to the shape and size of the lens to be ground. Within the housing 57 is a yoke 89 which engages a collar 90 on spindle 91 mounted for reciprocation in the housing. Interposed between the spindle 91 and the shaft 78 is a thrust bearing 92. A lever extends through and is mounted on the housing 57 and is provided with a cam 83 for actuating the yoke 89 for causing the pad 80 to be moved toward the pad 81 for clamping the lens between the two pads of the shafts 77, 78. The movement of the lever 83 in one direction will cause the spindle 91 to exert pressure on the shaft 78 for reciprocating it for either clamping the lens in position between the pads 80, 81 or for releasing the lens from engagement with the pads.

A pulley 41 is mounted on a shaft 42 journalled in the base 35 and power is transmitted to the pulley 41 from a pulley 40 on the arbor 36 through a belt 43. Motion from the shaft 42 is transmitted through the worm gear 44 thereof through a universal connection 45 to shaft 1. Gear housing 67 is mounted on one of the stanchions 52 and has a shaft 65 journalled therein. The shaft is connected by means of a compensating means 70 with a disk 69 on shaft 68. The shaft 65 is provided with a helical gear 66 adapted to mesh with a helical gear 59 on shaft 58. Shaft 58 is journalled in a bearing bracket 60 which is pivoted to the stanchion 52 by means of a shaft 61. A bracket 63 connected to the gear housing 67 supports a cam shaft 62 which is adapted to be oscillated by means of the handle 62' for oscillating the bracket 60 in establishing engagement between the gears 59 and 66. When these gears are out of engagement, the hand wheel 64 on the shaft 65 permits manual operation of the gear train 71, 73, 75 and 72, 74, 76 for manually turning the lens and pattern.

Shaft 58 is connected to shaft 2 by means of a universal connection 58' and shaft 2 is arranged in alignment with shaft 1, which shafts are capable of being engaged and disengaged through suitable clutch mechanism whereby intermittent motion may be imparted from the shaft 2 to the shaft 68 and gear trains.

78 The foregoing description is primarily based on

the standard machine, and hence forms no part of this invention except insofar as the drive mechanism is concerned with particular respect to shafts 1 and 2 and its related mechanism to now be set forth.

Referring particularly to Figures 1 to 4, the shaft 1 is provided at its upper end with a clutch ring 3 which is fixedly connected thereto. Surrounding the shaft 1 and clutch ring 3 is a sleeve 5 having a plurality of radial holes 95 formed therethrough in which balls 96 are mounted. The sleeve or ball cage 5 is supported on the shaft 1 by means of a collar 12 which is removably locked to the shaft. A coil spring 7 surrounds the sleeve 5 and has one end thereof 15 engaging the collar 12 and the other end fixed to the sleeve 5 so that upon the rotation of the shaft 1, the collar 12, sleeve 5 and clutch ring 3 all rotate as a unit.

Mounted on the lower end of shaft 2 is a 20 sleeve or outer clutch member 6 which has a sliding engagement upon the shaft 2 through a key 16 carried by the shaft and a keyway or groove 17 formed in the sleeve. The lower end of the sleeve 6 is provided with a clutch ring 4 25 having an outwardly and downwardly tapering surface which is adapted to engage the balls 96 for retaining them in the cage. The balls 96 travel on the inner surface of the clutch ring 4 and ride in recesses 13 formed in the outer face 30 of the clutch ring 3 on the shaft 1. When power is desired to drive the shaft 2 and shaft 1 is rotating, the balls 96 will be caused to travel in the recesses 13 where they will be impinged against the walls of the recesses and the inner 35 face of the ring 4 for locking the clutch members together whereby the motion of shaft 1 will be imparted to shaft 2, Figure 3. Upon the raising or moving of the sleeve 6 upwardly, the pressure on the balls is released and the tension of the 40 spring 7 is released causing the balls to be moved to the position as indicated in Figure 2 or in free running position.

Loosely mounted on shaft 1 is a sleeve 9 which is supported thereon by the collars 12 and 14 45 fixedly secured to the shaft 1. Mounted upon the sleeve 9 are two parallel plates 21 provided with slots 34 fitting around the sleeve 9. These plates are clamped together and about the sleeve 9 by means of clamping bolt 23 and their outer 50 ends are connected together by a transverse clamp bolt 24 similar to the bolt 23. Connected to the plates are stanchions 26 by means of the bolt 24 and dowels 25. Pivotedly connected to the stanchions are two parallel rods 27 hinged there- 55 to by means of a pin 28. The other terminals of the rods 27 are connected to a trunnion collar 10 carried by the sleeve 6 or outer clutch member, this collar 10 being held to the sleeve by means of a collar 11. Mounted on the plates 21 is a 60 cross plate 22 for supporting the magnet 18 by means of brackets 31 for the energizing coil 19. An armature 20 is connected to the rods or levers 27 by means of brackets 29. Magnet coil terminals 33 are mounted upon an insulated strip 65 32 carried by the plates 21 and suitably connected to the magnets 18.

The wires 100-101 of the circuit lead from a suitable source through a transformer, rectifier.

The electrical circuit consisting of the wires 70 100-101 extending from the contacts 33 to the seat 84, is provided with a suitable transformer, rectifier and condenser.

The sizer seat 84 is carried by an arm 102 connected to the hand wheel 85 which is supported 78

on the base 51. Suitable insulation 103 is interposed between the seat 84 and arm 102. The electric circuit from the terminals 33 extends to the sizer seat 84, one wire being connected to the seat 84 and the other wire to arm 102. The circuit is grounded on the machine as indicated at 104. The sizer seat 84 is mounted upon the table 51 and is capable of adjustment with respect to the pattern or former 79 on the shaft 77 so that as the former makes contact with the sizer seat 84, the electric circuit is established causing the magnet 18 to be energized and attracting the armature 20 thereto. The movement of the armature 20 into engagement with the magnet oscillates the rods 27 causing the trunnion collar 10 to force the outer clutch member 6 on the shaft 2 downwardly against the tension of the spring 8, interposed between the collar and end of shaft 1, for establishing an engagement between the two shafts.

The axial movement of the outer clutch member 6 into engagement with the inner clutch member causes an engagement between the downwardly tapering surface on the inner face of the clutch member 4 and the balls 96 carried by the cage 5, forcing the balls inwardly against the clutch ring 3 and causing them to roll across the circular recesses 13 against the pressure exerted by the spring 7 and wedging the balls between the rings 3 and 4 in a positive grip, as indicated in Figure 3. The shaft 1 which is rotating through its connection with the arbor 36, pulleys 40, 41 and belt 43, will now transmit this rotary movement to shaft 2 through the outer clutch member 6 which is keyed thereto. The rotation of shaft 2 will be transmitted to the gear 59 which is in mesh with helical gear 66 and the rotation of the gear 66 will cause power to be transmitted to shaft 65 through the compensating connection 69, 70 to shaft 68 of the carriage. The rotation of shaft 68 will cause the gears 71, 72 thereon to be rotated and motion will be imparted therefrom to the gears 73, 74. This movement will be imparted to the lens 82 and former 79 causing them to be rotated as clearly indicated in Figure 6. As soon as the lens 82 has been rotated sufficiently to again contact with the grinding wheel 46 and bringing a new surface to the grinding wheel to be ground, the former 79 will have passed out of engagement with the sizer seat 84 thereby breaking the electric circuit and allowing the armature 20 to become disengaged from the magnet and the outer clutch member 6 to move axially under the influence of the spring 8 away from the inner clutch member thereby declutching the shaft 2 from the shaft 1 and interrupting the rotation of the shaft 2, 68, 77 and 78.

When outer clutch member 6 is moved axially inward or downward additional pressure is placed on balls due to the tapering form of outer clutch member 4. As shaft 1 is turning carrying 3 and 5 this additional pressure due to the lay of 6, causes balls 96 to roll across circular recesses 13 carrying cage 5 with them, which is normally held in position shown in Figure 2 by spring 7, to the position shown in Figure 3, the engaged position. There are three sequences of action here that must be explained. Note Figure 2, balls 96 and ball cage 5 are held by spring 7 in a position where balls rest off center on sloping sides of circular recesses in Figure 2, the side in the direction of rotation of shaft 1. The balls are confined in this position by member 4. Any movement of member 4 inward or outward would result in a

change in position of balls 96 in recesses 13, and under no circumstances must balls be permitted to leave their respective recesses. The drag is between balls tending to mount the sides of recesses due to action of spring 7 but being prevented by outer clutch member 4 as 1, 3 and 5 turn and member 4 is stationary. As member 4 is moved inward or downward additional pressure is placed on balls due to taper of inner surface of member 4, the balls 96 then tend to roll down to 10 center of recesses at which point magnet 18 has drawn armature 20 into full contact and exerts its greatest pull, balls must continue to roll until they are wedged between the opposite sides of recesses and outer clutch member 4 as Figure 3. 15 As long as this downward pressure continues the clutch is engaged and driving its load. When the magnet releases it is to be noted that tapered inner surface of clutch member 4 tends to rise as pressure is released and spring 7 tends to return balls to their original position, see Figure 2. The clutch is engaged or operated without friction between outer clutch member 4, inner clutch member 3 and balls. As clutch closes on balls there is no friction as balls are free to roll and 20 they do roll until stopped solid as they wedge between members 3 and 4.

As the carriage is pivotally supported upon the stanchions 52 by the trunnions 53, 54, this carriage is capable of oscillating to and from the 30 grinding wheel 46 although it normally hangs substantially in a vertical position and as the lens during the grinding operation is held against rotation by the stationary gear trains against the face of the grinding wheel, the weight of the carriage 35 and the tendency for the carriage to move toward the grinding wheel holds the lens in position against the face of the grinding wheel. To insure of the lens being held against the face of the grinding wheel, a bracket 48 is connected to 40 the housing 57 of the carriage, upon which is mounted a weight 49 adjustably supported on a rod 50 of the bracket 48. By positioning the weight 49 along the rod 50, it can be readily determined the amount of pressure required for 45 insuring the lens being held against the face of the grinding wheel 46 to obtain the desired cutting action. Naturally as the lens is ground down to size or to the shape desired, there will be greater oscillation of the carriage as the former 79 50 contacts with the seat 84.

The driving connection between shaft 2 and 68 may be disconnected whenever desired by simply operating the handle 62 causing the cam shaft 62 to oscillate the bracket 60 and causing 55 the gear 59 to be moved out of engagement with the gear 66 whereupon the shaft 68 can be rotated by means of the hand wheel 64 and through the train of gearing 73, 75, 74, 76, the lens 82 and pattern 79 may be adjusted or examined to suit 60 the wishes of the operator.

In the operation of grinding the lens, which has been fabricated as prescribed by an optician, the proper pattern or former 79 is selected and mounted on the head spindle 77, and then the 65 lens is clamped between the pads 80, 81, by shifting the spindle 78 through the lever 83, cam 88 and yoke 89. Sizer hand wheel 85 is operated for setting the sizer seat 84 with respect to the former 79. The carriage which may be elevated or 70 swung by the handle 86 is now lowered allowing the lens to rest against the grinding wheel 46. During the preliminary assembly of the parts the gears 59 and 66 are generally out of mesh permitting the spindles 77, 78 of the carriage to be 75

operated through the hand wheel 64. However, as soon as the grinding operation is to be effected, the gears 59 and 66 are brought into engagement.

Upon the rotation of the grinding wheel 46 and setting the lens against the wheel 46, the lens will be grounded until the sizer seat 84 and pattern 79 contacts.

The carriage is being moved to the vertical due to the removal of the material from the lens and causing the pattern 79 to be brought closer and closer to the sizer seat, and upon the removal of the necessary quantity of material from the lens to conform to the shape of the pattern, the pattern will be brought into engagement with the sizer seat 84 and there will be no further grinding contact between the lens and grinding wheel. When the seat 84 and pattern 79 contacts, see Figure 6, an electric circuit is established, through the circuit between the seat and the magnet 18. The energization of the magnet 18 causes the armature 20 to be attracted and brought into engagement therewith, this action causes the rods or levers 27 to be oscillated on their pivot 28. The levers 27 will cause the outer clutch member 6 to be moved axially of the shaft 2, bringing the clutch member into engagement with the balls 96 of the cage 5 of the other clutch member carried by shaft 1.

The driving shaft 1 is being constantly rotated by the power transmitted from arbor shaft 36, so that the inner clutch member is being rotated. The cage 5 and balls 96 thereof are held against free rotation about the shaft 1 by the action of spring 7 which is connected to the cage 5 and collar 12 on the shaft 1. Normally there is a slight drag of the balls 96 against the outer clutch ring 4 of the clutch member 6, but not sufficient to cause the clutch members to be engaged until the clutch member 6 is moved axially under the influence of the levers 27, to bring it into a position to cause the balls 96 to be moved inwardly into the recesses 13 of the ring 3. This movement of member 6, due to the rotation of shaft 1 and cage 5 will cause the balls 6 to ride across the recesses 13 and exert a pressure between the rings 3 and 4 sufficient to lock the two clutch members together, whereupon motion is imparted to shaft 2 causing it to rotate gears 59, 66 and shaft 68. The rotation of shaft 68 will transmit motion to the spindles 77-78 through the gear trains and thereby cause the lens 82 and former 79 to be rotated for the purpose of bringing a new surface of the lens into engagement with the grinding wheel. It is to be noted that when contact is made between pattern 79 and sizer seat 84 the lens is out of contact with the grinding wheel and no further amount of glass is being removed therefrom.

Referring to Figure 6, the lens 82 is shown with several of its peripheral faces completed or ground to conform to the pattern 79, while the face against the wheel 46 is being ground and partially finished. The lower faces are still unground. This can be readily appreciated as the pattern and lens are rotated in a clockwise direction to bring new surfaces into contact with the grinding wheel. The sizer seat 84 has its outer face in the present instance curved substantially to the curvature of the grinding wheel 46, and it is this curved surface of the seat 84 that is engaged by the pattern 79, in regulating the amount of grinding to be done to the lens.

It should be noted that only a small amount of the glass or material is removed from the lens during the grinding operation, or at each inter-

val of contact of the lens with the grinding wheel and the interval of contact of the pattern with the seat 84. That is, the lens is ground during the period that contact is broken between the pattern 79 and seat 84 and until contact is again established between these members 79 and 84. Therefore, there will be numerous engagements and disengagements between the seat 84 and pattern 79, in grinding each face of the lens, or such faces as correspond to the faces of the pattern 79. The entire face is not removed at each engagement between the lens 82 and grinding wheel, but instead only a small portion, or so much of the lens as can be presented to the annular face of the grinding wheel. As a result, there will be numerous engagements between the pattern and seat for stopping the grinding operation, because the lens will be out of contact with the wheel when the pattern engages the seat 84. Of course, this engagement of the pattern with the seat establishes the circuit, and power is transmitted to the spindles 77-78 causing the pattern 79 and lens 82 to be rotated, but only sufficient to bring a portion of the lens into engagement with the grinding wheel and the pattern out of contact with the seat 84. It will be observed that the lens has been the sole support of the carriage with respect to the grinding wheel 46 and as the material of the lens is ground down until the former or pattern 79 contacts with the sizer seat 84 as illustrated in Figure 6 whereupon the grinding operation is stopped, although the grinding wheel continues to rotate. Upon the establishment of the circuit and the rotation of the spindles 77, 78, of the carriage, the lens 82 and former 79 are now rotated to bring a new surface of the lens into engagement with the grinding wheel, thereby elevating the carriage and causing the contact between the pattern 79 and seat 84 to be broken. Substantially one or two thousandths of an inch movement of the pattern 79 away from the seat will break the circuit and allow the magnet 18 to release the armature 20. The outer clutch member 6 will now automatically move axially away from the inner clutch member by the combined action of spring 8 and the wedge formation on the inner surface of outer clutch ring 4 due to the tendency of the spring 7 to return the balls 96 of the cage 5 to the opposite side of the circular recess 13 as indicated in Figure 2. The pressure on the balls is relieved upon the movement of the outer clutch member away therefrom and therefore the clutch members are released from engagement with each other and the balls and cage 5 are again returned to free running position as indicated in Figure 2.

The shafts 1 and 2 are therefore engaged and disengaged through a one way or over-running clutch, insuring practically an instantaneous engagement and disengagement of the shafts, without causing the spindles 77 and 78 to be over-driven in advancing the lens blank in contact with the grinding wheel, but only causing a movement of the blank sufficient to present a new surface to the grinding wheel. When the clutch is disengaged, and the pressure on member 6 is relieved by the magnet, the balls 96 are in the position indicated in Fig. 2, there is a slight drag as the cage 5 turns and ring member 4 is stationary. This prevents any backing up of the spindle gear train due to any friction between grinding wheel and lens blank, when lens blank is first set against grinding wheel. This drag is insufficient to turn gear train and spindle 75

assembly even when lens blank is raised off of grinding wheel.

The lens is now again held stationarily in contact with the grinding wheel as the gear trains will act as a brake against the rotation of the spindles 77 and 78. This cycle of operation is continued until all of the material of the lens has been removed in conformity with the shape desired by the pattern employed. One complete turn or revolution of the lens is sufficient generally to remove all of the glass and bring the lens down to proper size and shape. Of course, as the last amount of glass is removed the pattern and seat will again contact and the circuit will be established causing the clutch to be engaged between shafts 1 and 2 so that the spindles 77, 78 are again rotated and will cause the lens to be rotated. This rotation of the lens along with the rotation of the grinding wheel insures the removal of any superfluous glass that may affect a true shape or size of the lens. One revolution of the lens under this condition is generally sufficient. Of course, if there are any high spots left on the lens after the first revolution, the lens will contact with the grinding wheel and raise the carriage and break the circuit so that the lens will dwell or stop at this high spot until this material has been removed when the lens will immediately begin to rotate. The continuous turning or rotation of the lens with respect to the grinding wheel indicates to the operator that the lens is completed. With this method of removing the material and the forming of a lens production time is reduced from one half to one third compared with the general methods of the present time. This method entirely eliminates the constant stopping of the machine or carriage where the lens is continuously driven for the operator to examine the lens by "feel" to determine whether a sufficient amount of lens has been removed.

What I claim is:

1. In a lens grinding machine having a continuously driven grinding wheel and intermittently rotated head and tail spindles, said head and tail spindles supporting a pattern and a lens blank to be operated upon by said grinding wheel, means including a continuously rotative driving shaft and a driven shaft for imparting rotary movement to said spindles and lens blank, said driven shaft drivably connected to said head and tail spindles and having a slideable clutch element connected thereto, a clutch element fixed on said drive shaft, spring controlled ball means loosely mounted on said drive shaft and interposed between said clutch elements of said driven

and drive shafts and normally maintaining said clutch elements declutched, electro-magnetic means for exerting pressure on said slideable clutch element of said driven shaft for forcing it into engagement with said ball means and the other clutch element for causing said clutch element to be clutched, an electric circuit associated with said magnetic means and a pattern associated with said blank for intermittently making and breaking said circuit through said electro-magnetic means, said electro-magnetic means upon being deenergized relieving pressure on said slideable clutch element whereupon said ball means will automatically cause the clutch elements to be declutched and interrupting the movement of said lens blank.

2. In a lens grinding machine having a continuously driven grinding wheel and intermittently rotated head and tail spindles, said head and tail spindles supporting a pattern and a lens blank to be operated upon by said grinding wheel, means including a continuously rotative driving shaft and a driven shaft for imparting rotary movement to said spindles and lens blank, said driven shaft drivably connected to said head and tail spindles and having a slideable clutch element connected thereto, a clutch element fixed on said driving shaft, spring controlled ball means loosely mounted on said driving shaft and interposed between said clutch elements of said driven and drive shafts and normally maintaining said clutch elements declutched, electro-magnetic means for operating said movable clutch element, an electric circuit associated with said magnetic means, contact means in said circuit adapted to be intermittently engaged by said pattern for causing the magnetic means to be energized and deenergized, said magnetic means upon being energized exerting pressure on said movable clutch element for forcing it into engagement with said ball means and the other clutch element for causing said clutch elements to be clutched and imparting rotary movement to the lens blank and pattern, said pattern upon rotation being disengaged from said contact means and thereby breaking the circuit and deenergizing said magnetic means, said magnetic means upon being deenergized relieving the pressure on said clutch element whereupon said ball means will automatically cause the clutch elements to be declutched and interrupting the movement of said lens blank and pattern.

JAMES A. HARROLD. 55
